UNITED STATES PATENT OFFICE.

HENRY P. KRAFT, OF NEW YORK, N. Y., AND MAXIMILIAN CHARLES SCHWEINERT, OF WEST HOBOKEN, NEW JERSEY, ASSIGNEES TO A. SCHRADER'S SON, INCORPORATED, OF NEW YORK, N. Y., A CORPORATION OF NEW YORK.

TIRE OR OTHER VALVE.

1,187,154.

Specification of Letters Patent. Patented June 13, 1916.

Application filed September 5, 1905. Serial No. 277,053.

To all whom it may concern:

Be it known that we, HENRY P. KRAFT, residing in the borough of Brooklyn, county of Kings, city and State of New York, and 5 MAXIMILIAN CHARLES SCHWEINERT, residing in West Hoboken, in the county of Hudson and State of New Jersey, both citizens of the United States, have jointly invented certain new and useful Improvements in Tire 10 or other Valves, of which the following is a specification.

This invention relates to pneumatic valves for tires, and aims to provide an improved construction which will prevent the distortion 15 of the closing spring such as sometimes occurs with valves now in use; which construction is at the same time extremely cheap and is itself of ample strength.

Other improvements are referred to in 20 detail hereinafter.

The accompanying drawings illustrate embodiments of the invention.

Figure 1 is a longitudinal section with the valve closed. Fig. 2 is a longitudinal section with the internal parts in elevation, 25 showing the valve open. Fig. 3 is a view similar to Fig. 1 illustrating another means of obtaining the desired result. Fig. 4 is a similar section of another embodiment.

30 Referring to the embodiments illustrated, the valve comprises a shell A, a seat member B, a plug C carrying the seat member and screwing into a socket at the upper end of the shell, a valve stem D projecting above and below the valve proper E, a closing 35 spring F, a spring holder G, a packing ring H making an air tight joint between the seat member B and the shell A. In general these parts may be of any usual or suitable 40 construction and operation, the internal parts shown being adapted to be inserted in or removed from the shell at will by screwing in or out the plug C, which, for this purpose, is provided with a screw-driver 45 rib on its top adapted to be engaged by a complementary provision on the cap; these parts being, generally speaking, all old and well understood in the art.

When the valve is to be deflated the outer 50 end of the stem D is pressed downward to withdraw the valve proper E from its seat. Similarly when air is pumped into the tire the valve E is forced off from its seat. In both these operations the spring F is com-

pressed, and often with considerable force, 55 which produces a permanent distortion of the fine brass wire spring F and injuriously affects the operation of the valve.

According to this invention a simple, 60 cheap and strong stop is provided comprising preferably a member arranged between a fixed abutment and an abutment movable with the valve, and serving to limit the movement of the valve so that the spring F can only be compressed for a slight distance 65 sufficient to admit the full quantity of air past the valve. For example, the stop may consist of a small tube J of sheet brass or other metal surrounding the stem D. As illustrated in Figs. 1 and 2 the stop J may 70 be arranged between the lower face K of the valve proper and the top L of the spring holder G. The member J may be fixed to the spring holder G or to the under side 75 of the valve proper (or, equivalently, to the valve stem at a suitable height), but it can be more cheaply made as a loose tube through which the stem passes. When the valve is opened it cannot move farther than the position shown in Fig. 2, in which the 80 lower end K of the valve rests upon the stop J, and the lower end of the stop rests in turn upon the top L of the spring holder G. In this position the spring is not compressed to its limit, and thereby the distortion 85 which has previously caused difficulties is avoided. At the same time the danger of straining and bending the valve stem (which is necessarily of rather soft material and of small diameter) is avoided by the reinforcing effect of the surrounding tubular stop J. On the other hand the tubular stop J may 90 be arranged between the upper end M of the seat member B and a shoulder N formed by flattening the upper end of the stem D, as 95 shown in Fig. 4 or formed in any other suitable way on the stem. Here also it is to be observed that the stop J may be fixed upon the upper end of the seat member or upon the shoulder N or other fixed part of 100 the valve stem, the length of the member J being altered to suit the circumstances. Supposing it to be loose, as in the manner of Figs. 1 and 2, it is clear that upon pressing 105 down the stem D its movement is limited to the space between the abutment N and the upper edge of the tubular stop. This movement will be made less than the movement

necessary to completely compress the spring. Therefore the desired effect,—the saving of a sudden strain or blow upon the spring in its point of utmost compression, will be avoided.

Instead of forming the tubular sleeve J of sheet-metal, it may be formed of a closely wound spiral J' of fine wire, as illustrated in Fig. 3, so as to avoid the possible weakness introduced by the vertical joint in the sheet-metal tube indicated in Fig. 2.

Though we have described with great particularity of detail certain specific embodiments of our invention, yet it is not to be understood therefrom that the invention is limited to the specific embodiments disclosed. Various modifications thereof in detail and in the arrangement and combination of the parts may be made by those skilled in the art without departure from the invention.

What we claim is:—

1. A valve for tires or the like, including a valve proper E, a closing spring F, a 25 spring holder G, a seat member B, a valve stem D carrying said holder, spring, valve proper and seat member, and a stop for limiting the movement of said valve proper away from its seat to an amount less than 30 the play of the spring.

2. A valve for tires or the like, including a valve proper E, a closing spring F, a 35 spring holder G, a seat member B, a valve stem D carrying said holder, spring, valve proper and seat member, and a tube J surrounding the valve stem loosely and lying between said holder and an abutment on the valve stem, said tube J serving as a stop to limit the movement of the valve.

3. A valve for tires or the like, including a valve proper E, a closing spring F, a 40 spring holder G, a seat member B, a valve stem D carrying said holder, spring, valve proper and seat member, and a tube J surrounding the lower portion of the stem D

loosely and arranged between the spring holder G and the lower end K of the valve proper and serving as a stop to limit the movement of the valve.

4. A valve for tires or the like, including 50 a valve proper, a closing spring therefor, a seat member, a valve stem passing through said closing spring and seat member, and a stop carried upon said valve stem for limiting the movement of said valve proper away 55 from its seat to an amount less than the play of the spring.

5. A valve for tires or the like including a shell, a valve proper, a closing spring therefor, a seat member, and a stop located 60 below said seat member for limiting the movement of said valve proper away from its seat, said valve proper, closing spring and stop being connected so that they can be removed together from said shell.

6. A valve for tires or the like, including 65 a shell, a valve proper, a closing spring therefor, a detachable seat member within said valve shell, a valve stem passing through said closing spring and seat member 70 and a stop carried upon said valve stem and detached from said shell for limiting the movement of said valve proper away from its seat to an amount less than the play of the spring.

7. Internal parts of a valve mechanism comprising a valve-proper, a closing-spring therefor, and a stop beneath said valve-proper for limiting the movement of said valve-proper away from its seat, said parts 80 being connected together and adapted to be handled in connected relation.

In witness whereof, we have hereunto signed our names in the presence of two subscribing witnesses.

HENRY P. KRAFT.

MAXIMILIAN CHARLES SCHWEINERT.
